CLAIM

The ornamental design for a launching device as shown and described.

DESCRIPTION

FIG. 1 is a perspective view of a launching device according to the invention, showing the back and side of the launching device.

FIG. 2 is a perspective view of the launching device according to the invention, showing the front and side of the launching device.

FIG. 3 is a back view of the launching device.

FIG. 4 is a left side view of the launching device.

FIG. 5 is a front view of the launching device.

FIG. 6 is a right side view of the launching device.

FIG. 7 is a top plan view of the launching device; and, FIG. 8 is a bottom view of the launching device.

The broken lines disclosed on the drawing views form no part of the claimed design.
